UNITED STATES PATENT OFFICE.

SPENCER S. BEMAN, OF WINNETKA, ILLINOIS.

WINDOW STRUCTURE.

Application filed August 4, 1927. Serial No. 210,541.

My invention relates to an improved closure means and more particularly to a door or window having a frame in which a pane is mounted and to which a second pane is detachably fastened spaced from said first mentioned pane.

My invention primarily relates to a storm window of a new and improved type embodying all the advantages of the old type of storm window in which the two glass panes were each mounted in a separate sash, and yet is free of the various objections found in the old type referred to.

In the average building, seventy-five per cent of the heat loss is through window glass which may be largely eliminated by providing windows having two panes mounted in spaced relation to each other. If desired, the panes may be of glass, in which case they will not materially affect the vision or passage of light therethrough. Such a structure affords a substantial saving of fuel and produces a room practically free of drafts and one which is more evenly heated.

One of the objects of my invention is to provide a closure, such as a door or window, which has two panes, preferably of glass, mounted on a single sash, one of said panes being detachably secured.

Another object of my invention is to provide a window comprising a sash of the customary type having a pane permanently mounted therein with a second pane positioned to engage the side thereof, and having fasteners mounted in the side of said sash and adapted to releasably engage and hold said second pane in position.

Another object of my invention is to provide a removable pane for doors or windows of customary type, and fasteners therefor, said pane being readily installed and detachably held in position on either the inside or outside face of the sash.

Another object of my invention is to provide a detachable pane for a pair of sliding window sashes having permanently mounted panes therein, said detachable panes being mounted on the faces of said sashes, each positioned outside the path of travel of the other sash whereby interference is avoided when the sashes slide past one another.

These and other objects are accomplished by means of the arrangement disclosed on the accompanying sheet of drawings, in which—

Figure 1 is a cross sectional view of a dou-

ble sash window, each sash of which is equipped with my improved window pane positioned on the inside;

Figure 2 is a similar view showing a double window sash construction similar to that shown in Figure 1, in which my improved window pane is attached to the outside thereof;

Figure 3 is a fragmentary elevation showing the attaching clips for holding the pane detachably against the face of the window sash.

Figure 4 is a perspective view of a modified form of attaching clip;

Figure 5 is a fragmentary sectional view of a double sash window showing an application of the clip shown in Figure 4;

Figure 6 is a similar sectional view in which the second window pane is inset with respect to the sash and showing application of a similar clip and also a spring plate release member.

The various novel features of the invention will be apparent from the following description and drawings and will be particularly pointed out in the appended claims.

Referring to the drawings, it will be noted that my invention is to be applied to a closure of customary type, such as a window comprising two slideable sashes 10 and 11 positioned in a frame 12 and mounted in the usual manner. Sash 10 constitutes the lower portion of the closure and has on the outer surface a recess 13 in which is positioned a glass pane 14 held by putty 15 or any other suitable means. The upper sash is constructed in a similar manner, being provided with a pane 16 held by putty 17 and having a portion 18 engaging the lower sash along the surface 19 whereby the sashes in the position shown in Figure 1 effectively close the opening in the window frame. The upper and lower sashes are provided with a lock 20 comprising a locking lever 21 and a loop 22 of the customary type. In the form of my invention shown in Figure 1, the second pane 23 is of glass and is positioned against the inner face of the sash 10, engaging edgewise the metallic plates 24. These plates are held by any suitable means, such as screws 25, against the side of the sash 10 and are provided with a second plate 26 adapted to pivot when the screw 25 is loose but to be firmly held in position when the screw 25 is tightly screwed down. The

100
105
110

second plates 26 are pivoted eccentrically so that in one position they may present a portion which will overlie the glass pane 23 when in mounted position to effectively secure the same in position. However, the pane may be readily removed by merely loosening the screw 25 and turning the plate 26 to its opposite position where no portion thereof overlies the pane 23. The upper sash 11 is provided with a similar pane 23 and one which is mounted in the same fashion as that on the lower sash 10, the only difference being that it is provided with a cut-away portion at 27 so that it may arch over the locking element 22.

Referring now to Figure 2, corresponding parts bear the same reference numerals as those in Figure 1, the only difference being that this modification shows the pane 23 mounted on the outside of the sashes 10 and 11, in which case the locking plates and screws are fastened on the opposite faces of the sashes.

It can be readily appreciated that this auxiliary window pane can be readily attached to the customary type of window or door and may be of glass or any other suitable material for this use. Its value resides in the fact that it affords a dead air space in the window structure thereby providing all the advantages realized in storm windows and provides a structure which is free of all the objections in the old type of storm window. It may be quickly installed and after it is installed, the pane may be quickly removed and put back. Among the many advantages, it does not interfere with the visible quality of the window, it cuts down the heat loss, and eliminates drafts and all tendency of condensation of frost on the window. This invention permits free operation of windows at all times and the auxiliary glass can be put on and taken off from inside the house in actually a few seconds time. The auxiliary glass provides an unbroken surface permitting quick washing and is further a type which requires no upkeep, such as painting, putting, etc. The fasteners for mounting the auxiliary glass are simple in structure and are inconspicuous, being preferably finished to match existing hardware.

A modified clip 28 of spring material may be used if desired, said clip having a flat base portion 29 which may be pivotally secured to the sash by a screw 30, having a seat or shoulder 31 for receiving and supporting the edge of the auxiliary glass and having a yieldable inwardly bent finger 32 for yieldably retaining said glass in position. In Figure 6 the auxiliary glass is inset within a groove 33 in the sash and a similar spring retaining clip 34 applied. In addition, mounted within the groove at spaced points are spring release members 35, one of which is shown in Figure 6. When the clip 34 is

withdrawn the release member 35 will press the glass outwardly into a position wherein it may be gripped by the hand. The release member has an exposed grip portion 36 whereby it may be hand operated if the glass is stuck in position.

I claim:

1. Closure means comprising a sash having a pane therein, a second pane spaced from said first pane positioned against the side of said sash, plates fastened to said sash engaging edgewise said second pane, and other plates movably mounted on said first named plates overlying said second pane and forming detachable fasteners therefor.

2. In a window structure, the combination of a sash, a pane therefor and a fastener comprising a plate engaging edgewise said pane, and a second plate on said first named plate overlying said pane, means for mounting said plates and for permitting movement of said upper plate whereby said pane may be removed to form a detachable fastener for said pane.

3. Closure means comprising a sash having a pane positioned against the side thereof, and fasteners therefor mounted on said sash, said fasteners being movable, and each having a shoulder to engage the edge of said pane.

4. Closure means comprising a sash having a pane positioned against the side thereof, and fasteners therefor mounted on said sash said fasteners being movable, and each having a shoulder to engage the edge of said pane, and a spring extension to overly the edges of said pane, whereby said pane is yieldably maintained in position.

5. Closure means comprising a sash having a portion adapted to receive a pane, a pane therein, and a spring means between said sash and pane, and means to hold said pane in position.

6. Closure means comprising a sash having a portion adapted to receive a pane, a pane therein, a spring means exerting an outward pressure on said pane, mounted between said pane and sash, and means for detachably holding said pane in position.

7. Closure means comprising a sash having a portion adapted to receive a pane, a pane therein, a spring means, exerting an outward pressure on said pane, mounted between said pane and sash, and a resilient means mounted on said sash for holding said pane in position, said last named means exerting a pressure opposed to said first named outward pressure.

8. Closure means comprising a sash having a portion adapted to receive a pane, a pane therein, a spring means exerting an outward pressure on said pane, mounted between said pane and sash, and means for detachably holding said pane in position, said spring means having a portion extending beyond the edge of said sash whereby it may be manually engaged to remove the same.

9. Closure means comprising a sash having an opening adapted to receive a pane, a pane therein and a second pane larger than said opening held against the side of said sash and spaced from said first mentioned pane.
10. Closure means comprising a sash having an opening adapted to receive a pane, a pane therein and a second pane larger than said opening positioned against the side of said sash and spaced from said first mentioned pane, and fasteners therefor.
11. Closure means comprising a sash having an opening adapted to receive a pane, a pane therein and a second pane larger than said opening positioned against the side of said sash and spaced from said first mentioned pane, and readily detachable fasteners therefor.
12. Closure means comprising a sash having an opening therethrough and a pane
- larger than said opening positioned against the side thereof and fasteners mounted on said sash detachably holding said pane against displacement.
13. Closure means comprising a pair of sashes movable relative to each other and each having an opening therethrough, readily detachable panes larger than said openings mounted on the side of said sashes, each positioned outside the path of travel of the other sash whereby interference is avoided during movement of said sashes.
14. Closure means comprising a sash having an opening therethrough and a pane larger than said opening positioned against the side of said sash and resilient fasteners for detachably holding said pane in position.

Signed at Chicago, Illinois, this 19th day of July, 1927.

SPENCER S. BEMAN.
